UNITED STATES PATENT OFFICE

JOHN K. LENCKE AND HERMAN SCHMID, OF KINGSTON, NEW YORK, ASSIGNEES TO APOLLO MAGNETO CORPORATION, A CORPORATION OF DELAWARE

ELECTRIC GENERATOR CONSTRUCTION

Application filed October 24, 1929. Serial No. 402,162.

This invention relates to casings and parts for electric generators and particularly magneto generators commonly used for ignition systems for internal combustion engines.

5 An object of the invention is to provide simple, cheap and efficient casings for the working parts of the generator easily produced and easily replaced in case of damage.

Another object is to provide that the several main casings and certain associated parts are produced by die casting or moulding so as to require a minimum of hand work for their production.

15 A further object is to provide a generator wherein the insulating casings such as the collector, distributor and other parts subjected to high voltage are of simple and rigid construction.

20 A further object of the invention is to provide generator parts of simple construction that will not give trouble in service and which may be easily replaced.

25 Further objects will be apparent to those skilled in the art and are briefly referred to hereafter.

In the accompanying drawings:

Figure 1 is a side view, partly in perspective, of a magneto generator employing casings embodying this invention;

30 Figure 2, a view partly in section of the base member of the magneto;

Figure 3 is a front view of the base member;

35 Figure 4 is a view partly in section of the frame member of the magneto which forms a unit;

Figure 5 is an end view of the frame member looking into the armature bores;

40 Figure 6 is a front external view of the collector cover;

Figure 7 is a sectional view on the line e, f, Figure 6;

45 Figure 8 is a rear internal view of the cover, Figure 6;

Figure 9 is an external view of the end plate or plates for the open end of the main frame, Figure 4;

50 Figure 10 is a view of the inside of the end plate, Figure 9;

Figure 11 is a sectional view of the end plate, Figure 9.

By way of illustration, the magneto Figure 1 is shown as designed for use with a six cylinder engine for supplying ignition current thereto, but can be designed for any other number of cylinders. The present application will therefore be largely limited to describing and claiming specific details of construction of the casings and parts made integral therewith or imbedded therein, particularly as the manufacture and sale of these parts or casings for replacements constitutes a business, it is desired to protect by patent as distinguished from the business protected by patents on the magneto as a whole. Applicants therefore herein claim the specific construction of the specific parts described herein and usually sold as repair or replacement parts, the sale of which often constitutes a separate business from that of the sale of complete magnetos.

The numeral 1 denotes the base member as a whole, forming part of the casing of the magneto upon which all other parts are supported. This has a bottom portion 2 which is commonly tapped for bolts, whereby the base may be secured to the engine. These tapped holes are shown in dotted lines and it is sometimes desirable to secure the magneto to the engine by a clamp passing over the magneto using the tapped holes for locating dowel pins. As such clamps are well known they are not described in detail. The base member has a portion 3 preferably formed integral therewith and at right angles to the base 1. This is formed with an outwardly extending boss 4 provided with the internal shoulders 5, 6, 7, whereby a shaft 8 and its front bearing may be supported within the boss. Two or more holes 9, 10 may be provided in the face of 3, to engage pins or bolts in the main frame, one of which bolts is shown at 11.

The upper rear surface 12 of boss 4 on the flange 3 is made to fit against and below the shoulder 13 of the main frame shown in Figure 4. The lower portion 14 of the base is made to fit the inner flange 15 of the main frame, and dowel pin 16 in the frame may

also engage corresponding aperture 17 in the base thereby aligning the same with the frame member.

The base, Figure 2, being moved to the right under Figure 4, the bolt 11 will enter hole 9 and the bolt 18 will enter a hole in the projection 19 at the rear of the base. There is a corresponding bolt 11a to enter hole 10 at the front and a corresponding bolt 18a at the rear. The flange 19a for rear bolt 18a is shown in Figure 3.

The foregoing design of base plate enables it to be easily constructed by die casting and permits the bearing portion to be cast integral therewith and the complete base member to be easily assembled to the main frame, Figure 4, the parts being accurately lined up by the engaging pins and surfaces, and firmly secured in operating position by the bolts as described.

Oil cups 20, 20a may be provided having ducts communicating with the interior of that portion of the boss 4 supporting the shaft bearing whereby the same may be lubricated. And a flange 21 is provided on each side of the base, set back from the extreme outer edge thereof to which the magnet strap 22 extending over the magnets 23, 23a, may be secured by means of screws on each side, the screws on one side being shown at 24, 24a and the arrangement on the other side not shown being the same. A recessed portion 21a is formed between the flanges 21 for containing a magnet clamping means, which is secured by a screw through the threaded hole 21b.

The main frame Figure 4 forms with its associated parts, mounted upon or cast therein, a unit. It may be a die casting having the bolts previously referred to cast therein or attached thereto in any suitable manner. This frame also carries four pole pieces of the usual type, two of which are shown at 25, 26. These pole pieces extend through to the outer surface of the frame and contact with the magnets 23, 23a and form the inner faces of the circular bores 27, 28 for the armatures of the magneto generator. Concentric with these bores are the slightly larger bores 29, 30 to give the ends of the armature additional clearance, and concentric with 29, 30 are the slightly larger bores 31, 32 for gears attached to the armatures for driving the same.

The bore 33 is provided in which to mount a bearing for the shaft 8 and the bore 34 to provide a space for a gear on said shaft which engages the gear in 32.

The front end of the frame is provided with apertures 35, 36 and bores 37, 38. In the latter are mounted the outer ball races 39, 40 of the bearings for the armatures.

An oil cup 41 is provided having a duct 42 connecting with the race 39 and a similar cup 41a and duct (not shown) is provided

for oiling the race 40. An oil cup 43 and ducts 44, 44g are provided to admit oil to the ducts 44b, 44k in the end plate, Figure 20, and from these ducts the oil flows to the bearing 65 therein. Similar ducts 44c, 44d are provided communicating with bearing 66.

The finished flanges 45, 46 are placed in the ends of the openings 35 and 36, Figure 4, and may be inserts in the main frame when it is made, or may be put in afterward.

The shoulders 47, 48 are provided to form seats for the collector covers shown in Figures 16, 17, 18 and hereinafter described.

Suitable webs 49, 50, 51 are provided to stiffen the frame and the magnet flanges 52, 53 are provided to prevent sidewise movement of the magnets 23, 23a which are located between them. The opening 54 is provided to hold a sleeve or spacer between the bearings located in 5 and 33, one end of this sleeve partially engaging 5 and 54 and the other end engaging the shoulder 55.

The washer 56 may be placed between the main frame and the base member to insure a tight joint at this point.

This main frame, Figure 4, also forms part of the external casing of the magneto and it will be observed can be made and sold as a unit complete with the parts heretofore described as attached to or imbedded therein, such as the pole pieces 25, 26, and that it can be easily disassembled from the base member, Figure 2, and the other parts of the casing hereinafter described.

The interrupter end plate, Figures 9, 10, 11, consists preferably of a die casting, or castings 57, 57a, 57b, adapted to be attached to the main frame by screws, one of which is shown at 58, Figure 1, and for which clearance holes, some of which are shown at 59, are provided. Tapped holes, some of which are shown at 60, Figure 5, are provided for these screws in the main frame. Outwardly extending bosses 61, 61a are provided upon which may be mounted the usual interrupter casings, one for each armature, the upper one being shown at 62 in Figure 1.

This plate has the annular depressions 63, 64 concentric with the armature bores 27, 28 in which are placed the outer ball races 65, 66 and the insulation 65a, 66a for the armature bearing. Openings 67, 68 permit the armature shafts to extend out into the interrupter casings 67a, 68a which contain the usual interrupter mechanisms. These end plates, or a single plate if 57, 57a and 57b are made integral, forms a cover for the gears in the unit frame.

The opening 69 is provided so that shaft 8 may extend therethrough and into a housing 70 for a gear carried on 8 to drive a gear on a shaft leading to the distributor mechanism in casing 71.

The housing 70 is clamped by means of

screws to the end plate 57 (when the end plate is made in one piece) or to the bottom portion thereof designated by the numeral 57b when the end plate is in three pieces. This housing carries a grease cup 70a for supplying grease to the gears therein and has a clamp portion 73 in which may be clamped, by means of screws pressing the portion 73, the neck or shank of a distributor head and mechanism which is supported thereby.

The collector casings are shown in Figures 6, 7 and 8. As both are alike, only one will be described in detail. These consist of the bakelite or other mouldings of insulating material and are shown in position at 103 and 104 in Figure 1. These are provided with terminals 99, 99a which connect via cables with terminals 76 and 77 in the distributor head. These terminals 99, 99a connect with springs, one of which is shown at 104, Figure 7, which springs connect to rotating contacts on the armatures which contacts are, in turn, connected to the secondary or high tension windings.

These casings are provided with the recess 105 for the spring 104 and a recess 106 to permit the end of the armature carrying the high tension contact to project therein to contact with 104. The tapered flanged portion 107 is provided to contact with the shoulders 47, 48 on the main frame. The casings are secured to the main frame by screws into the frame passing through holes 108 in the edge of the casings.

For the sake of brevity the drawings and description in this application have been confined to the features herein claimed.

We claim:

1. In an electric generator, a base having a projecting portion forming a bearing support, a frame having two armature bores therein, and means on said bearing support and frame for securing said members together.
2. In an electric generator, a cast frame, a plurality of pole pieces therein, bearing members in one end of said frame, and downwardly projecting portions on said frame having means for securing said frame to a base.
3. In an electric generator, a unit frame having a portion forming a housing for a driving shaft and gear and forming a support for one of the bearings for said shaft, two armature bores in said frame and an extended portion on the frame forming a casing for the armature gears.

4. In an electric generator, the combination of, a supporting frame, two sets of pole pieces therein, bearing members, oil cups, and bolts whereby the frame may be attached to a base, all of the foregoing being assembled and constructed to form a unit part.
5. In a frame for an electric generator, as

claimed in claim 4, magnet flanges on the frame extending over the top and down the sides thereof.

6. A frame for magneto generators having a main body portion constituting a housing for two armatures and a portion forming an end for said housing portion and bearing supports, said frame having a laterally extended portion forming a gear casing, and a cover for the gear casing end of the frame, said cover forming a bearing support.

7. In a magneto generator, in combination with a unit frame having two armature bores therein, end plates adapted to be secured to the end of said frame said plates enclosing said armature bores and forming bearing supports, and laterally projecting bosses on the outer surface of said plates forming interrupter supports.

8. In combination with a main frame having two parallel armature bores therein and an end portion forming bearing supports, collector casings of insulating material adapted to be mounted on said end portion and to close the open ends of said frame.

In testimony whereof we affix our signatures.

JOHN K. LENCKE.
HERMAN SCHMID.
